APPARATUS FOR CONTROLLING ENGINE IDLING SPEED

Elmer Olson, Rochester, N. Y., assignor to General Motors Corporation, Detroit, Mich., a corporation of Delaware

Application June 15, 1954, Serial No. 436,872

5 Claims. (Cl. 74—472)

This invention relates to carburetors for internal combustion engines and more particularly to carburetors provided with mechanism for automatically controlling the engine idling speed under certain operating conditions.

It has been found that under conditions which cause the under-hood temperatures to get considerably higher than normal, the engine does not idle satisfactorily, operating unevenly and tending to stall. This higher than normal under-hood temperature is encountered in the event of prolonged idling of the engine on vehicles equipped with air conditioning apparatus, and, in fact, the difficulty can be encountered in any automotive vehicle on a day when atmospheric temperatures are very high in the event of prolonged idling. Therefore, it has been found desirable, in the event of prolonged idling, to step up the idling speed and this is automatically accomplished in the copending application of Olson et al., S. N. 379,401, filed Sept. 10, 1953, now Patent No. 2,762,235, dated September 11, 1956, by mechanism controlled by the transmission control lever and effective to increase the idling speed whenever said lever is moved to its neutral position.

It is not desired to increase the idling speed when the vehicle is stopped for a brief period, as is generally the case when waiting for a traffic-light, for example. When the idling period is relatively brief, the temperature does not as a rule get high enough to produce any difficulty with respect to the idling operation. Moreover, under these conditions the transmission control lever is usually permitted to remain in drive position. In a vehicle with a synchro-mesh transmission, the clutch is generally disengaged and with an automatic transmission, the position of the control lever is not changed when such a stop is made.

It is the primary purpose of the present invention to provide a simplified means for increasing the idling speed when the engine idles with the transmission control lever in neutral position and this is accomplished by a suction operated member which moves a movable idle stop to a position to increase the opening of the throttle to some extent when the transmission control lever is in its neutral position. When the control lever is in this position, the load on the engine is slightly less than when the lever is set in drive position in a vehicle equipped with an automatic transmission and also with a synchro-mesh transmission the load is slightly less when the control lever is set in neutral than when such lever is set in a gear engaging position with the clutch disengaged. Due to this reduction in load, there is a slight increase in engine speed and this increase in speed will cause a slight increase in engine suction, or partial vacuum maintained between the throttle and the engine which is utilized to move a diaphragm connected to the movable idle stop. Movement of the diaphragm effects movement of the idle stop in a direction to move the throttle a little further toward open position so as to further increase the engine speed.

Further objects and advantages of the present inven-

2

tion will be apparent from the following description, reference being had to the accompanying drawings wherein a preferred embodiment of the present invention is clearly shown.

5 In the drawings:

Figure 1 is a side elevation of a conventional carburetor equipped with the device which is the subject of the present invention;

10 Figure 2 is a detail section through the diaphragm housing; and

Figure 3 is a detail view of the mounting of the stop operating lever; and

Figure 4 is a diagrammatic view, showing the carburetor of Fig. 1 and associated controls.

15 For convenience of illustration, the device which constitutes the present invention is shown in the drawings as mounted on the housing of a carburetor such as illustrated in the copending application of Olson and Dermond, S. N. 264,136, filed December 29, 1951, now Patent No. 2,771,282, dated November 20, 1956. This carburetor is what is generally termed the four-barrel type, having four separate outlets connecting with four separate passages formed in the intake manifold, but so far as the present invention is concerned, it is entirely immaterial whether the carburetor with which it is associated is of single or plural outlet construction. Also, the specific internal construction of the carburetor is of no importance, so far as the present invention is concerned and, therefore, to simplify the illustration only 30 the outside of the carburetor is shown in elevation.

The carburetor shown is formed of three separate castings, an air inlet casting 2, through which air flows into the carburetor, casting 4 immediately below casting 2, in which the fuel chamber is positioned and in which the 35 mixing chamber, where fuel is mixed with air to form a combustible mixture, is also positioned. The casting 4 is secured to and supported by the outlet or throttle body casting 6, which is provided with the usual attaching flange 8 for securing the carburetor to the intake manifold of an engine 9 in the usual way.

In the casting 6 there are a plurality of primary mixture outlets and a plurality of secondary mixture outlets, one primary outlet 10 and one secondary outlet 12 being indicated by dotted lines. The outlets 10 are controlled 45 by throttle valves 14 and the outlets 12 by throttle valves 16, only one of each of said valves being shown in the drawings. The primary throttles are secured to a shaft 18 and the secondary throttles to a shaft 20, both of which are suitably journalled for rotation in the 50 wall of the casting 6.

The primary throttles 14 are open at all operating speeds and after a predetermined opening movement of such throttles the operation of shaft 18 effects movement of the shaft 20 to open the secondary throttle valves.

55 To effect this operation, the shaft 18 has secured thereto an operating arm 22, having formed therein a slot 24 in which is received the bent-over end 26 of an operating link 28, the other end of which is pivotally connected to an operating arm 30, secured to the secondary throttle 60 shaft 20. In the carburetor shown in the above application the shaft 18 has an operating arm secured to its opposite end which is moved by the usual throttle operating mechanism to rotate the shaft 18 in a counter-clockwise direction in order to effect opening movement of throttles 14. For convenience of illustration, this throttle 65 operating connection, including a rod 25 and accelerator pedal 27, is shown herein as connected with the arm 22, but obviously it could be connected to another arm as in the earlier application.

70 The arm 22 is moved counter-clockwise to open the throttles 14 and after the arm moves a predetermined amount, the right end of slot 24 engages the end 26 of

link 28 and moves arm 30 in a clockwise direction to open the secondary throttles 16. A spring 32 tends to hold the secondary throttles closed. The mechanism so far described, with the exception noted, is substantially the same as that fully shown and described in the above-mentioned pending application.

The primary throttles 14 occupy a very nearly closed position for normal idling and this position is determined by an adjustable stop screw which engages a fixed lug projecting from the carburetor housing. The stop screw is carried by an arm on the opposite side of the shaft 18 and engages a lug on the opposite side of the carburetor housing. This mechanism is not shown but is of the same construction as shown in the above-mentioned application. The stop screw is set in adjusted position to give the desired normal idle speed.

As already indicated, means are provided, according to the present invention, for moving the primary throttles 14 slightly toward open position when the engine 9 is idling with the transmission 31 in neutral, such means being operated by engine suction. This mechanism includes an adjustable stop screw 40 threaded in an ear 42 extending laterally from a lever 44 pivoted on a pin 46 secured in any suitable way to a bracket 48 and extending laterally therefrom. To prevent any appreciable movement of the lever 44 axially with respect to the pin and to hold the parts in proper alignment, any suitable means may be provided. For example, as shown in Fig. 3 the end of pin 46 may be of reduced size, as indicated at 50, and a nut 52 be screwed thereon with a suitable lock washer 54 to hold the nut in place. The screw 40 is adjusted so that its position with reference to arm 22 is such as to give the desired result.

The supporting bracket 48 is integral with a plate 56 which extends upwardly and at its upper end is integral with a flat horizontal plate 58 which extends over and is secured by screws 60 to the top of the fuel chamber which is a part of the casting 2. The plates 56 and 58 form a supporting bracket and a reinforcing rib 62 may be provided to increase the rigidity of the bracket.

Secured to the supporting plate 56 is a diaphragm housing indicated generally by the numeral 70 and formed of two sheet metal shells 72 and 74, the circumferential edge of shell 72 being crimped over the edge of shell 74 to form a fluid-tight joint, and a flexible diaphragm 76 of suitable material is clamped between the peripheral edges of the shells. Extending into the shell 72 is a sleeve 78 which has a reduced part 80 extending through a central opening formed in shell 72 and also through the supporting bracket 56, the end of part 80 being spun over as indicated at 82 to clamp the plate and shell 72 against a shoulder formed at the junction of the reduced part 80 and the enlarged part of the sleeve. The latter serves as a bushing in which a pin 84 connected to the diaphragm slides, when the engine suction effective on such diaphragm varies.

The diaphragm and two reinforcing washers 86 and 88 positioned on opposite sides of the diaphragm are mounted on a reduced portion of a stud 84 which is riveted as indicated at 90 to hold the parts in assembled position. Positioned between the washer 88 and the rivet-head 90 is a cup-shaped washer 92, which receives one end of a spring 94 positioned between such washer and the housing 74, such spring being effective to hold the parts in the position shown in Fig. 2 when there is no suction effective on the diaphragm. When the parts are in this position the throttles 14 are closed to an extent determined by the normal stop which has been described, but is not shown.

An adjusting screw 96 may be mounted in any desirable way in the shell 74, if desired, and may be adjusted to determine the position to which the diaphragm can be moved by engine suction which is communicated by pipe 98 to the inside of shell 74, such pipe being connected to the intake passage at some suitable point between the

throttles 14 and the engine. The pipe 98 may be connected to shell 74 by any suitable means and as shown, has a flange 100 which is clamped between a nipple 102 secured to the shell and a clamping nut 104 which is screwed on the nipple.

Any increase in suction effective on the diaphragm 76 will move the throttles 14 toward open position. To this end the stud 84 is connected to the upper end of lever 44 by a pin and slot connection, the lever having a slot 106 into which a pin 108 projecting from the stud 84 extends, as indicated in Fig. 1. Obviously, a movement of the diaphragm to the right will move the upper end of lever 44 to the right and the stop 40 to the left to effect counter-clockwise movement of arm 22 and opening movement of throttles 14.

The manual operating linkage for the throttles includes a lost motion device adjacent its point of connection with arm 22, so that this slight movement of the throttles can be effected without any movement of the throttle operating linkage. As shown, the throttle operating linkage includes a rod 110 which is connected by suitable operating connections, not shown, to the usual foot operated accelerator pedal. This rod is integral with or suitably connected to a tubular member 112 into which the enlarged part 114 of a rod 116 extends. The rod 116 is pivotally connected by a pin 118 in a slot 120 formed in the arm 22 and a spring 123 is positioned in the tubular member 112 between the end thereof and the left end of element 114.

The tubular member 112 has slots 124 near its right end and extending through these slots is a pin 126 which also extends through a hole in the element 114 and is held in position by a cotter pin 128. The spring 123 normally holds the parts in the position shown in Fig. 1 and when the accelerator pedal is depressed to open the throttles, the rod 110 is pulled to the left and the pin 126 being in the right end of the slots, the link 116 is also pulled to the left to open the throttles. When the stop 40 is moved to the left, as previously described, the movement of element 114 merely compresses the spring 123 and does not move the rod 110 and operating connections extending from such rod to the accelerator pedal, the usual accelerator return spring being stronger than the spring 123.

To illustrate the operation of the device, let it be assumed that the engine 9 is idling and the transmission 31, if of the automatic type, is set in "drive" position by a transmission control lever 131 and if of the manual control type, is set in some gear engaging position with the clutch disengaged. The throttle will be closed to an extent determined by the ordinary idle stop, or possibly by stop 40, and the transmission gearing is being rotated slowly by the engine. If the transmission control lever 131 is moved to neutral position, the load on the engine is somewhat reduced, by reason of the fact that the transmission gears are not being rotated. This will cause a slight increase in engine speed, and the increase in speed will, in turn, cause a slight increase in the suction effective on diaphragm 76 and a slight movement of stop 40 to the left to effect a slight increase in throttle opening.

It will be understood that when the engine is not operating the usual idle stop, which is not shown, will determine the closed position of the throttle, and when the engine is running the position of the throttle, when idling cold, will be determined by the fast idle stop, as shown in the above-mentioned. When idling hot, the throttle position may be determined either by the normal idle stop or the stop screw 40.

As the throttle is opened in the manner described, the suction posterior to the throttle begins to fall, for reasons well known. This tends to offset the effect of increased engine speed and after a slight opening movement of the throttle, these effects are balanced and the throttle stops in a slightly more open position than before the control lever was shifted to neutral. The valve stops

when the force exerted by suction on the diaphragm is balanced by the spring 94 and this occurs after a slight opening movement of the valve. This opening of the throttle is slight, but enough to effect sufficient increase in idling speed to obtain satisfactory idling operation. It will of course, be understood that in the particular carburetor shown, the position of both throttles 14 is controlled in the manner described but the stop mechanism disclosed can be employed in a single outlet carburetor to control the position of the conventional single throttle valve.

While the embodiment of the present invention as herein disclosed constitutes a preferred form, it is to be understood that other forms might be adopted.

What is claimed is as follows:

1. Apparatus for controlling the idling speed of the engine of an automotive vehicle comprising in combination, a carburetor for supplying a combustible mixture of fuel and air to said engine and having a throttle valve for controlling the quantity of mixture supplied thereto, suction operated means for moving the throttle toward open position for increasing the idling speed of the engine, and a control means movable to different positions to control the operation of the vehicle, said control means being movable to a position reducing the load on the engine thereby causing the suction effective on the suction operated means to be increased and the throttle to be moved to a further open position.

2. Apparatus for controlling the idling speed of the engine of an automotive vehicle comprising in combination, a carburetor for supplying a combustible mixture of fuel and air to said engine and having a throttle valve for controlling the quantity of mixture supplied thereto, suction operated means for moving the throttle toward open position for increasing the idling speed of the engine, and a transmission control lever movable to different positions to control the operation of the vehicle, said control lever being movable to a position reducing the load on the engine thereby causing the suction effective on the suction operated means to be increased and the throttle to be moved to a further open position.

3. Apparatus for controlling the idling speed of the engine of an automotive vehicle comprising in combination, a carburetor for supplying a combustible mixture of fuel and air to said engine and having a throttle valve for controlling the quantity of mixture supplied thereto, suc-

10
5

tion operated means for moving the throttle toward open position in order to increase the idling speed of the engine, a transmission control lever for controlling the operation of the vehicle transmission, said control lever being movable to a position reducing the load on the engine thereby causing the suction effective on the suction operated means to be increased and the throttle to be moved to a farther open position, a manually operable means for actuating said throttle valve, and a lost motion connection in said last named means to permit relatively unresisted movement of said throttle by the suction operated means.

4. An idling speed controlling apparatus as defined in claim 3 in which said lost motion connection comprises telescoping members connected by a pin and slot connec-

15

5. Apparatus for controlling the idling speed of the engine of an automotive vehicle comprising in combination, a carburetor for supplying a combustible mixture of fuel and air to said engine and having a throttle valve for controlling the quantity of mixture supplied thereto, suction operated means for moving the throttle toward open position in order to increase the idling speed of the engine, a transmission control lever for controlling the operation of the vehicle transmission, said control lever being movable to a position reducing the load on the engine thereby causing the suction effective on the suction operated means to be increased and the throttle to be moved to a farther open position, an operating arm for said throttle, a manually operating connection extended to said arm, a member operable by said suction operated means and also engaging said operating arm to move said throttle toward open position upon an increase of suction, said operating connection including telescoping members connected by a pin and slot connection, whereby movement of the 20
25
30
35
40
